UNITED STATES PATENT OFFICE

2,175,594

SLED

Walter Eberhardt, Chicago, Ill.

Application April 10, 1939, Serial No. 267,039

2 Claims. (Cl. 280—12.11)

My invention relates to a means for propelling sleds by manual operation by a person sitting thereon.

The principal object of my invention is the provision of independent lever controlled mechanism attached to each side of the sled supplying proper propulsion for a sled, and arranged to be controlled and operated manually; each hand operating independently a set of levers so that the sled may be propelled either in a forward direction or by manipulating one side in a certain manner it may effect the steering of the said sled either to the right or left.

A further object of the invention is the provision of simple means in order to cancel or nullify the lifting moment resulting from the translation of radial motion to direct forward motion.

Another object of my invention is to provide a simple, durable, efficient, and useful device which can be manufactured economically in quantity production.

Other features may become apparent from the ensuing description and the accompanying drawing wherein like symbols are used to designate like parts and in which:

Fig. 1 is a side view of a sled to which is attached my invention.

Fig. 2 is a top view of Figure 1.

Fig. 3 is a longitudinal cross-sectional view on the line 3—3 of Figure 1.

Fig. 4 is a cross-sectional view on the line 4—4 of Figure 1.

Referring to the drawing in Figure 1, 6 denotes, generally, a sled which is made up of a top supporting member designated by the numeral 16, resting on two runners designated by the numeral 8 and having curved portions at the forward end designated by the numeral 17.

40 The runners are provided with props or supports designated by the numeral 7, having recessed portions 18 for lightness and strength, which support the upper platform designated by the numeral 16.

45 The front portion 7 of the runners is provided with a boss designated by the numeral 9 adapted to receive a connecting pivot shaft designated by the numeral 10 having a head 11 on one side and a threaded portion on the other adapted to receive a nut designated by the numeral 12.

This structure is provided in order to support the levers designated by the numerals 13, which have a hole adapted to be pivoted on the rod structure 10. These levers have a channel section as indicated by the numeral 15, and a hub

extension designated by the numeral 19 for purposes to be later explained.

Within the channel portion 15 and at the hub portion 19 is mounted a propelling lever designated by the numeral 28 and having a sharp edge 5 or point designated by the numeral 29 which is adapted to anchor to the ground when the combined levers are moved in a direction of the arrow to the dotted position so as to effect their propelling action of the sled in a forward direction.

The levers 13 are supplied with suitable handle portions designated by the numeral 14, and are drilled in order to receive the pivot unit designated by the parts 21 and 23. The portion 21 is 15 a stud having a threaded hole designated by the numeral 22 adapted to receive the screw designated by the numeral 23.

These two screw studs secured together help to hold in place the spring 24 having one extension 25 anchored to a hole 27 drilled in the lever 13 the other extension 26 anchored at a point in a hole of the lever 28, the coil portion of the spring being coiled about the body of the screw 23.

It will be noted that in the lever 13, I provide a slot 20 which is adapted to take up the lifting moment of the lever 13 when it is moved from the full position to the dotted position. Since, in the arc it describes, there is a small chordal distance which the lever 13 would have to traverse or lift the sled as a result of the arcuate motion; by providing the lost motion of slot 20, I nullify the lifting moment and translate the radial action or motion of the lever 13 into a direct horizontal motion of the sled thus completely eliminating 30 the lifting moment involved.

In order to operate my invention, a person desiring to take a ride on the sled, will sit on the platform 6 facing toward the front of the runners, the curved portions 17, and by propelling 40 the levers 14 in a direction shown by the arrow to the dotted position, both of the levers being operated simultaneously a forward propelling action will result.

The slot 20 aiding in providing a true translation of the arcuate motion to the forward propelling motion eliminating the lifting moment because of the lost motion provided by the said slot 20.

When it is desired to steer the sled from its 50 straight and direct forward course, by operating the left lever, the sled will be steered or diverted to the right, and vice versa, by operating the right lever and holding the left lever motionless the sled will steer to the left.

Up to the present time sleds are usually built in a manner whereby it is necessary for someone either to pull the rider along, or a rider usually grasps the sled up against his body, runs with it to acquire enough momentum, and then throws his body down on the sled in order to travel along for a distance, until all of the momentum or potential energy is consumed.

With my sled, that will not be necessary, it can be more conveniently operated and propelled, and may be used on horizontal surfaces, where the sled may be moved along by virtue of the mechanism I have supplied and expounded herein as the subject matter of my invention.

Altho I have described in succinct terms the structure and description of my invention, and inasmuch as it may be susceptible of many alterations, modifications, and improvements, I reserve the right to all such alterations, modifications, and improvements coming within the scope of my invention and within the purview of the appended claims, it being understood that my invention is to be limited only by the prior art and the subjoined claims.

Having thus described my invention what I

claim as new and desire to secure by Letters Patent is:

1. A device of the character described comprising, an operating lever articulately mounted on each side of a sled, the said operating lever provided with an elongated slotted bearing, a propelling lever mounted swivellably and slidably in said elongated bearing, and means for securing said propelling lever in said elongated bearing comprising, a male stud engaging a female stud, 10 the said combined leverage mechanism adapted to propel a sled.

2. A device of the character described comprising, an operating lever articulately mounted on each side of a sled, the said operating lever 15 provided with an elongated slotted bearing, a propelling lever mounted swivellably and slidably in said elongated bearing, means for securing said propeller lever in said elongated bearing comprising, a male stud engaging a female stud, 20 and spring means adapted to maintain the said propelling lever in contact with the ground, the said combined leverage mechanism adapted to propel a sled.
